AIR CONDITIONER FRONT PANEL

Carl W. Sundberg, Bloomfield Hills, Mich., assignor to
Whirlpool Corporation, a corporation of Delaware

Application February 10, 1958, Serial No. 49,570

Term of patent 14 years

(Cl. D62—4)

Figure 1 is a front elevational view of the air conditioner front panel showing my new design.

Figure 2 is a cross sectional view taken substantially along line 2—2 of Figure 1.

I claim:

The ornamental design for an air conditioner front panel, as shown.
